INNER SPRING MATTRESS

Burt R. Noel, Milwaukee, Wis., assignor to Marquardt Company, Milwaukee, Wis., a corporation of Wisconsin

Application March 12, 1934, Serial No. 715,118

7 Claims. (Cl. 5—351)

This invention relates to improvements in inner spring mattresses.

It is an object of the invention to provide means whereby the premade side border of a spring filled mattress may not only be connected more adequately to the body of the mattress, but may also be employed as a means of covering an inner roll at the margin of the mattress, thus dispensing with the prior art practice of using a separate strip of felt for padding to fill the gaps left in the formation of the inner roll.

In the drawing:

Figure 1 is a cross sectional view of a fragmentary portion of a spring filled mattress embodying this invention.

Figure 2 is a cross section through a premade quilted border prior to its application to the mattress in the process of assembling thereof.

Figure 3 is a detail cross section through the quilted border in the plane of the handle.

Like parts are identified by the same reference characters throughout the several views.

The assembly of helical springs is conventional. It is covered above and below with a sheet of burlap 4. At this point the premade quilted border is applied about the sides of the spring set and connected with the burlap.

As shown in Fig. 2, the premade quilted border comprises a plurality of plies held together at intervals by staples. There is an inner ply of sheeting at 5, a ply of felt at 6, an intermediate ply of sheeting at 7, an outer ply of felt at 8, and a ply of mattress ticking 9 which covers the exposed surfaces. These several plies are quilted with wire staples 10 whereby the premade border may be handled and applied as a unit.

The height of the inner ply 5 of sheeting is such that its margins can be folded over on to the burlap sheets 4 and stitched thereto as shown at 11. The spring set is now completely encased in the upper and lower sheets of burlap 4 and the interconnecting ply 5 of the border, which is stitched to the burlap.

Felt plies 15 and 16 are now placed upon the burlap sheets 4, and are substantially co-extensive therewith. Over these, throughout the perimeter of the mattress, are folded the free marginal portions 17 of the felt ply 6 of the border. These marginal portions are then covered in turn by the outer felt plies 18 and 19 which cover the faces of the mattress, and the layers of sheeting at 20 and 21 are used to cover the felt layers 18 and 19. These layers of sheeting are stitched along the corner margins of the mat-

tress at 22 to the edges of the intermediate ply 7 of sheeting in the preformed border, thus making a second casing.

The inner roll 25 is now made in the usual manner by a well known machine which engages the sheeting plies 7 and 20 at some little distance from the line of stitching at 22, compresses them toward each other to form the end of the felt ply 18 into a roll, and then maintains the roll by stitching to the felt as shown at 26.

The process of forming this reinforcing roll leaves a substantial hollow at each side of it. In accordance with the present invention the felt ply 8 of the preformed border is made sufficiently high so that its marginal portions 28 may be passed completely about the roll 25 to overlie and underlie the sheeting plies at 20 and 21 on the upper and lower faces of the mattress.

The top and bottom plies of ticking 29 and 30 are now used to cover the upper and lower faces of the mattress and are connected along their margins with the ticking ply 9 at the preformed border, the seam being preferably covered by a tape at 31 to complete the mattress.

The fact that the border is preformed makes it easily possible to provide a very substantial handle for the mattress. The handle 35 is mounted on a pair of handle posts 36 flanged at 37 to engage the outer ticking ply 9 and riveted at 38 upon a clamping and spacing plate 40. Since the border is formed as a complete unit prior to its assembly in the mattress, the riveting operation at 38 comprises a means by which the handle may easily be affixed to the preformed border, without the difficulties which would be encountered in any attempt to attach a handle of this kind after the mattress had been completed.

It is particularly to be observed that there are no loose pieces of felt employed in this mattress, and the preformation of the border with pieces of felt and sheeting of differing widths makes it possible to interleave the felt plies of the border with those of the top and bottom of the mattress in a novel manner and one calculated to bind the whole mattress together in a unitary structure which is more durable than has previously been the case. Also much labor and expense in manufacture is saved by reason of the construction herein disclosed, while producing a superior structure which is more satisfactory than those previously used.

I claim:

1. As a new article of manufacture, a border

55

- unit separately produced for use in mattress construction, said unit comprising a plurality of plies of felt of differing height for connection at different points with top and bottom mattress plies, and inner, outer, and intermediate plies of fabric, together with means permanently interconnecting all of said plies in operative assembly for unitary handling.
2. As a new article of manufacture, a pre-formed border constructed as a unit for use in mattress production, such border comprising a succession of alternate plies of fabric and felt, a successive ply of each material being increased in height over a preceding ply of the same material, together with means permanently interconnecting all of said plies in operative assembly for unitary handling.
3. A mattress comprising a central resilient filler, a top section comprising a plurality of plies of material, a bottom section comprising a plurality of plies of material and a side section comprising a plurality of plies of material, the plies of the side section being interleaved with the plies of the top and bottom sections.
4. A mattress comprising a resilient filler, a fabric case for said filler, and a plurality of plies of padding material covering contiguous side surfaces of said case, and interleaved with each other adjacent the corner intervening between said side surfaces, the plies of at least one of said surfaces being extended about said corner to be interleaved with the plies of the other.
5. A mattress construction comprising the combination with a spring filler having fabric sheets above and below and a plurality of plies of padding material upon said sheets, of a border com-

prising a fabric inner ply connected with said sheets, to thereby form a casing for the spring filler, a marginal padding ply interleaved between the padding plies above and below said sheets, a second fabric case enclosing said filler and the several plies aforesaid, means connecting the walls of said second case adjacent the margins thereof to provide a roll, a border ply of padding material covering the side of said second case and extending about said roll to overlie the marginal portions of the top and bottom of said second case, and an outer case of ticking or the like completely enclosing the mattress.

6. As a new article of manufacture, a pre-formed mattress border comprising a plurality of padding plies each materially higher than the finished height of the border, and means connecting permanently the intermediate portions of said plies, their upper and lower margins being free from each other for a substantial portion of their height, whereby to be available to be separately interleaved with the corresponding padding plies of the top and bottom of the mattress body.

7. As a new article of manufacture, a pre-formed mattress border comprising a plurality of fabric plies including an inner and outer facing for said border and at least one intervening padding plies materially higher than the finished height of the border, and means connecting said fabric and padding plies together permanently at their intermediate portions, the upper and lower margins of the several plies being free of each other for independent connection with the top and bottom portions of the mattress body.
